UNITED STATES PATENT OFFICE

WILLIAM N. LOBER, OF REAMSTOWN, AND WILLIAM E. HAUSHOUE, OF ADAMSTOWN, PENNSYLVANIA

DESIGN FOR A TABLE TOP

Application filed January 4, 1932. Serial No. 42,367. Term of patent 14 years.

To all whom it may concern:

Be it known that we, WILLIAM N. LOBER and WILLIAM E. HAUSHOUE, citizens of the United States of America, residing at Reamstown and Adamstown, respectively, in the county of Lancaster and State of Pennsylvania, have invented a new, original, and ornamental Design for a Table Top, of which the following is a specification, reference being had to the accompanying drawings, forming a part thereof.

We claim:—

The ornamental design for a table top as shown.

WILLIAM N. LOBER.
WM. E. HAUSHOUE.
